UNITED STATES PATENT OFFICE

CYRUS HAWKINS, OF CAMDEN, NEW JERSEY, ASSIGNOR TO HIRES, CASTNER & HARRIS, INC., OF PHILADELPHIA, PENNSYLVANIA, A CORPORATION OF DELAWARE

CLOTH WIPER FOR POWER-PLATE PRINTING

Application filed January 7, 1925. Serial No. 973.

My invention relates to wipers for plates used with printing and embossing presses and is particularly applicable to plates carried by an endless chain.

5 A purpose of my invention in its complete embodiment is to wipe, clean and polish a plate by passing it successively across a number of rolls, each roll presenting fabric or similar material against the surface of the 10 plate.

A further purpose is to present an arcuate wiping surface to a moving plate.

A further purpose is to use a continuing length of the same material, preferably cloth, 15 successively first as a wiper, then as a cleaner and then as a polisher.

A further purpose is to longitudinally jig a roll presenting cloth or like material against a plate, to make its polishing, cleaning and/or 20 wiping action more effective.

A further purpose is to gear together and to 25 positively and adjustably drive rolls adapted successively to present cloth against a moving plate, in order to maintain a uniform but adjustable feed of cloth between the rolls.

A further purpose in the combination claimed is to provide a friction connection between a positive driving element and a spool which is receiving used wiper material.

30 A further purpose is to adjustably moisten material used successively, considered in the order of use of a particular part thereof, as a wiper, as a cleaner and as a polisher, at any one or all of three places, i. e., before the polishing, cleaning and wiping rolls respectively.

A further purpose is to provide a roll wiper interchangeable with existing pad wipers.

40 Further purposes will appear in the specification and in the claims.

I have preferred to illustrate my invention by one only of the many forms in which it may be used, selecting a form however which is convenient and efficient in operation and which illustrates particularly well the principles involved.

Figure 1 is a broken elevation and illustrates my invention somewhat diagrammatically in position of use, wiping a plate.

Figure 1^a is a portion of Figure 1 to enlarged scale.

Figure 2 is a top plan view of the structure shown in Figure 1 but omitting the plate.

Figure 2^a is a portion of Figure 2 to enlarged scale. 55

Figure 3 is a section of Figure 2, taken upon the line 3—3 and to enlarged scale.

Figure 4 is an enlarged fragment from Figure 1. 60

Figure 5 is a fragmentary section taken on the line 5—5 of Figure 4.

Figure 6 is a broken rear elevation of detail parts seen in rear section elevation in Figure 3. 65

Figure 7 is a left end elevation of Figure 6.

Figure 8 is a right end elevation of a portion of the structure seen in Figure 6.

Figure 9 is a side elevation of a detail sleeve seen also in Figures 6 and 7. 70

Figure 10 is a diagrammatic view on reduced scale showing the path of the wiping material.

Like numerals refer to like parts in all figures. 75

Describing in illustration and not in limitation and referring to the figures:—

In the illustration a usual form of wiper support is shown mounted beneath a plate-carrier 15. It comprises vertical slotted guide and support members 16 and 17 on opposite sides of the carrier and arms 18 and 19 keyed to the rocker shaft 20. These arms in turn adjustably support the members 16 and 17. 80

The rocker shaft pivots in fixed bearings 21 and 22 in opposite stationary portions 23 and 24 of the frame of the press. It is operated to vertically position the slotted members 18, 19 by means of hand wheel 25. This wheel has a hub 26, internally threaded to receive the threaded upper end of rod 27 and externally threaded to receive a nut 28 beneath the fixed hub bearing 29. This swivels the hub. 85

The rod 27 carries pin 30 at its lower end which pin pivots in a fork 31 of the outer end of an arm 32 keyed to the rocker shaft. 90

The vertical slots 33 in the members 16, 17 cooperate with fixed transverse rods 34 and 35 to form a vertical guide for the support. Threaded holes 36, 37, 38 and 39 near the ends 100

of the members 16, 17 provide convenient means interchangeably for connection to a usual pad wiper or for connection to the mechanism of my invention.

5 In that usual wipers are well known and do not in themselves form part of my invention, I have not shown them in the drawings.

The mechanism of the invention is carried upon transverse rails 40 and 41 which are secured by screws 42, 43, 44 and 45 entering holes 36—39. End members 46 and 47 fastened to and along the rails 40 and 41 carry the side members 48 and 49. The side members at their ends are fastened to the end members by screws 50, 51, 52 and 53.

The side members 48 and 49 are bored at 54 and 55, 56 and 57 and 58 and 59 to form opposite bearings for the shafts 60, 61 and 62 of the rolls 63, 64 and 65. The side members are bored also at 66 and 67, 68 and 69 and 70 and 71 to form bearings for the idler shafts 72, 73 and 74.

The rolls 63, 64 and 65 are preferably covered circumferentially with rubber or other resilient material and are placed substantially tangential with the path of the bottom surface of the plate 75 carried by the carrier 15. Vertical adjustment at the wheel 25 permits bringing these rolls to exactly the proper height irrespective of differences in the thicknesses of plates used.

The roll shafts are rearwardly extended beyond the side member 49, spur gears 76, 77 and 78 being keyed to the extended portions and the extreme ends being rounded, at 79, to provide substantially axial engagement with jiggers 80 which are intended to push the roll shafts in an endwise direction.

The forward ends 81 of the roll shafts are bored and counterbored at 82 and 83 to receive the inner ends of pins 84 and surrounding springs 85. A washer 86 is located preferably in each counterbore to receive the end of the spring. The springs 85 are compression springs, with outer ends supported against a stationary strip 87 which is mounted from the side member 48 upon posts 88. The outer ends of the pins 84 are fastened against axial movement in the strip 87 as shown at 89. The arrangement is such that the springs 45 press the rolls axially inward so as to maintain the rounded inner ends of the roll shafts continually pressing against the jiggers 80.

55 Posts 90 and 91 mounted respectively on the rails 40 and 41 near their inner ends provide bearing support for the cam shaft 92 and for a shaft 93 upon which the jiggers 80 loosely pivot.

The cam shaft is provided with a gear 94 to which it is keyed. The gear is driven in any convenient manner, not shown.

65 The jigging operation is effected by the cooperative action of the cams 94 rigidly fastened to the cam shaft, the jiggers 80 loosely pivoted on the shaft 93 and the springs 85.

The sectional shape of the cams is generally oblong with rounded ends. These ends successfully engage the toes 95 of the jiggers and as the jigger members turn to permit the cams to pass the toes the heels 96 engage the rounded ends of the roll shafts, pushing these shafts axially against the retractive forces of the springs 85, which latter maintain the roll shafts in continual contact with the heels of the jiggers.

70 The wiper material 97 unwinding from a delivery spool 98 is led successively under the idler shaft or roller 74, over the polishing roll 65, under the idler roll 73, over the cleaning roll 64, under the idler 72, over the wiping roll 63, to wind up on the receiving spool 99. The rolls 73 and 72 are so called because they have been given another function than mere giving tension and direction to the material and, if not given the added functions, could be shafts or bars.

75 Fork bearings 100 and 101 for the delivery spool are carried by brackets 102 and 103 which are respectively fastened to the end 47 by screws 104 and 105. A strap 106 fastened by screws 107 to the cross piece 47 passes over the delivery spool. A suitable weight 108 is fastened to its lower end, providing proper friction resistance to unwinding of the delivery spool. Any desired resistance is obtained by varying the weight 108.

80 The receiving spool 99 is supported upon brackets 109 and 110 fastened to the end 46 by screws 111 and 112.

85 One end 113 of the shaft of the receiving spool rests in a fork bearing 114 of the bracket 110. The other end 115 of the shaft of the receiving spool fits into a slotted sleeve 116 which is rigidly screwed to the inner end of a headed shaft 117. A projecting pin 118 through the shaft 115 fits the slot 119 of the sleeve 116 so that the receiving spool and shaft 115 turn together. The shaft 117 turns in the closed bearing 120 in the end of bracket 109.

90 The ratchet feed for an adjustable but uniform feed of the material 97 successively over the different rolls from the delivery spool to the receiving spool is best seen in Figures 115 4 and 5.

95 The shaft 117 is extended in front of its bearing 120 to provide pivot support for the feed arm 121, ratchet cover 122 and ratchet wheel 123. The wheel has a hub 124 which is frictionally pressed against the inner shoulder 125 of a head 126 at the outer end of the shaft.

100 The hub 124 of the ratchet wheel carries rigidly fastened to it a sprocket wheel 127 and is externally threaded at its outer end to receive a cap 128. A compression spring 129 is placed within the cap and is adjustably compressed between the bottom of the cap and the outer end of the shaft 117 to pro-

vide an adjustable friction engagement between the shaft and the ratchet member.

The feed arm carries a pawl 130 which engages teeth 131 of the ratchet. It is moved up and down in any suitable way by the operation of the press. As shown the end 132 of the main driving shaft of the press is provided with an eccentric pin 133 and a link 134 between this pin and the outer end of the feed arm operates the feed arm.

It is desirable to make the feed adjustable which may be done in any convenient way. In the illustration the adjustment is by means of the ratchet cover 122 which is set by a screw 135 carried by an arm 136 of the cover. It engages the hub of the bearing 120. As the feed arm moves down the pawl first engages and then rides over the cover at 137 and the effective length of each stroke is thus determined by the position of the cover.

The spur gears 138, 139 and 140 are mounted upon the rearwardly extended ends of the idler shafts 72, 73 and 74 which, meshing with the roll gears 76, 77 and 78, constitute with the latter gears a train whereby the rolls are geared together and must move in unison.

If desired the gear 140 may be dispensed with, and the gears 138 and 139 may be loose with respect to their shafts allowing slippage. However, I have thus far preferred to have the idler shafts driven by their respective gears.

The rolls 63, 64 and 65 being of the same diameter and carrying the same size gears, 25 76, 77 and 78 respectively, have the same circumferential rate of feed, and if desired the idler rolls 72, 73 and 74 may also be given the same circumferential speed by providing proper relation between their diameters and the size of the gears 138, 139 and 140. Usually 40 however, I deem it preferable not to do this because of the greater cost of driving the shafts and because of the greater compactness to be secured. I therefore permit slippage 45 of the material 97 at the idler rolls, as in the arrangement illustrated.

The train of rolls is positively driven from the ratchet wheel 123 carrying sprocket wheel 127, a sprocket wheel 141 being provided on the extended end of the shaft 72, and driven by a sprocket chain 142 from the wheel 127.

It is desirable to be able to moisten the material 97 before any one or each of the rolls 65, 64 and 63 respectively, and to an adjustable extent.

This may be done in any convenient manner. In the illustration means is provided for adjustably applying moistening at each of the idler rolls. The mechanism shown is the 60 same at each of the idler rolls. The moistening unit shown comprises a water reservoir 143 in which are provided a lower (water) feed roll 144 supported in fixed bearings 145 and 146 and an upper (water-applying) roll 65 147 adjustably supported in housing bearings

148. The ends of the shaft of the applying roll 147 extend out somewhat from the bearings 148 and when in place are supported upon inclined bearings 149 which are adjustably sloped so as to bring the applying roll in contact with the material 97 where it lies against the idler roll.

The sloping bearings 149 for the ends of the shaft of the moisture applying roll are mounted upon a frame structure 150 provided at opposite ends with hook members 151 and 152 hooking over the idler shaft. The idler shaft is shown of reduced size at the ends. A short loose round sleeve 153 is shown under the hook 152. The hook 151 fits about a non-circular portion 154 of a sleeve 155. This sleeve surrounding the reduced end of the idler shaft is provided with a round portion which passes through the side member 48. A crank arm 156 is fastened to it outside of its bearing in the member 48 and the crank is angularly set to give any desired slope to the inclined bearings 149 by means of a screw 157 engaging any one of a series of holes 158 arranged in an arc, about the idler shaft.

Adjustment of the degree of moistening at any one of the idler shafts is made by changing the slope of the inclined bearings 149 by means of the crank 156 and its screw 157, which changes the pressure of the applying roll against the material 97 against the idler shaft.

In operation the feed is adjustable but at any adjustment is uniform and proportionate to the speed of the press. The feed arm 121 positively drives the different rolls through link 134 and eccentric pin 133 on the driving shaft 132. At the same time it frictionally winds up the receiving spool causing uniform feed from the delivery spool to the receiving spool. Continuous jiggling of the rolls 65, 64 and 63 makes the respective polishing, cleaning and wiping operations more effective, the material being used first as a polisher at the roll 65, then as a cleaner at the roll 64 and finally as a wiper at the roll 63, the material becoming increasingly dirty as it passes the successive rolls so that by the time it reaches the receiving spool it is ready for replacement or cleaning.

For certain types of plates the old type of wipers are desirable and for this reason my structure is made interchangeable with old type wipers, permitting the use of either structure according to the type of plate used.

In view of my invention and disclosure variations and modifications to meet individual whim or particular need will doubtless become evident to others skilled in the art and I claim all such in so far as they fall within the reasonable spirit and scope of my invention.

Having thus described my invention, what I claim as new and desire to secure by Letters Patent is:

1. In a plate printing press, a movable plate repeatedly inked and at the place of inking movable in one direction only, a delivery spool, a receiving spool spaced therefrom, a strip of wiping material unwinding from the delivery spool and winding on the receiving spool, a plurality of rolls over which the strip is led between the spools and by which it is presented as a plurality of wiping surfaces in the path of the inked surface, and a common feed for the rolls and receiving spool, frictionally winding the spool and positively feeding the rolls. 70
2. In a plate printing press, a movable plate repeatedly inked and at the place of inking movable in one direction only, a delivery spool, a receiving spool spaced therefrom, a strip of wiping material unwinding from the delivery spool and winding on the receiving spool, a plurality of rolls over which the strip is led between the spools and by which it is presented as a plurality of wiping surfaces in the path of the inked surface, means for longitudinally jigging the rolls out of step with each other and other means for feeding the strip. 75
3. In a plate printing press, a movable plate repeatedly inked and at the point of inking movable in one direction only, a strip of wiping material, a plurality of rolls carrying the strip and presenting it as a plurality of wiping surfaces in the path of the inked surface, and means before different rolls for moistening the strip to different extents for different rolls. 80
4. In a plate printing press, a movable plate repeatedly inked and at the point of inking movable in one direction only, a strip of wiping material, a plurality of rolls carrying the strip and presenting it as a plurality of wiping surfaces in the path of the inked surface, an intergearing between the rolls adapted to drive them in the same direction at the same speed, and a forward feed for the intergearing. 85
5. In a plate printing press, a movable plate repeatedly inked and at the point of inking movable in one direction only, a delivery spool, a receiving spool spaced therefrom, a strip of wiping material unwinding from the delivery spool and winding on the receiving spool, a plurality of wiper rolls to which the path of the plate is substantially tangential and presenting the strip as a succession of wiping surfaces, intermediate guides supporting the strip in a tortuous path between the wiper rolls, intergearing between the wiper rolls adapted to feed the rolls in the same direction at the same speed, and a common feed for the intergearing and the receiving spool, frictionally winding the spool and positively feeding the gearing. 95
6. In a plate printing press, a movable plate repeatedly inked and moving in the same path, a delivery spool, a receiving spool spaced therefrom, a strip unwinding from the delivery spool and winding on the receiving spool, means intermediate the spools for presenting the strip at spaced intervals into the path successively as a wiper, a cleaner and a polisher, and means for forwardly feeding the strip between each two intervals. 100
7. In a plate printing press, a movable plate repeatedly inked and at the point of inking movable in one direction only, a delivery spool, a receiving spool spaced therefrom, a strip unwinding from the delivery spool and winding on the receiving spool, means intermediate the spools for presenting the strip at spaced intervals into the path successively as a wiper, a cleaner and a polisher, and other means for moistening the strip for wiping, cleaning or polishing. 105
8. In a wiper, the combination of a plurality of parallel rolls, shafts therefor, a strip passing successively over the rolls to present different contacts for a plate, and positive means engaging the shafts to jig the rolls out of step with each other. 110
9. In a wiper having spaced rolls for presenting a strip of wiper material successively at spaced intervals against a moving plate, means for longitudinally jigging the rolls comprising shafts respectively mounting the rolls, a rocker arm at one end of each shaft limiting its position in one axial direction, a cam shaft, cams thereon operating the respective rocker arms and resilient means at the other end of each shaft pressing it against its rocker arm. 115
